DUPLEX HEAD NAIL MACHINE

Robert A. Little, Donora, and Joseph A. Rice,
Belle Vernon, Pa., assignors to The American
Steel and Wire Company of New Jersey, a cor-
poration of New Jersey

Application October 18, 1943, Serial No. 506,742

9 Claims. (Cl. 10—43)

The present invention relates to improvements in that type of nail machine adapted to form a duplex head on a piece of nail stock at a single blow.

Although it is broadly old to provide means for forming a duplex head on a piece of nail stock at a single blow, in the machines of the prior art excessive wear takes place, causing frequent shut-downs of the machinery for replacement and repairs. A primary object of the present invention is to provide an improved construction and arrangement of pinch die parts which will have a long life and withstand the shocks to which mechanism of this type is repeatedly subjected.

A further object is to provide improved feeding means for advancing the nail stock to the pinch dies.

Another object is to provide a construction and arrangement for accurately coordinating the action of the head-forming pinch dies with the feed carriage.

An additional object is to provide a construction and arrangement whereby the pinch dies and feeding means can be adjusted to suit the requirements of nails of different sizes.

Another object is to so combine and coordinate the various instrumentalities hereinafter described in detail that they singly and jointly perform the functions set forth.

The above and other related features of the invention will be more fully apparent from consideration of the following detailed disclosure and the appended claims when read in connection with the accompanying drawings.

In the drawings:

Figure 1 is a plan view of a duplex head nail machine embodying a preferred form of the present invention, with parts broken away and shown in section in the interests of clarity.

Figure 2 is a side elevation of the nail machine of Figure 1, with parts shown in section.

Figure 2^a is a detail of the feed cams.

Figure 3 is a transverse vertical section on line III—III of Figure 2.

Figure 4 is a transverse section on line IV—IV of Figure 1.

Figure 5 is an enlarged horizontal section illustrating chiefly the pinch dies and related mechanism.

Figure 6 is an enlarged vertical longitudinal section taken on line VI—VI of Figure 5.

Figure 7 is a detail plan view of a secondary pinch die holder showing means for supporting

the secondary pinch die therein, with freedom for movement relative thereto.

Figure 8 is a section on line VIII—VIII of Figure 7.

5 Figure 9 is an end view of Figure 8 with a portion broken away and shown in section to better illustrate means for guiding the secondary pinch die and limiting the relative movement thereof in its holder.

10 Figure 10 is a detail section through the secondary pinch dies and holders therefor when they are in retracted position.

Figure 11 is a view similar to Figure 10, but showing the secondary pinch dies gripping the 15 nail stock and a head-forming hammer in the act of upsetting portions of the nail stock.

Figure 12 is a view similar to Figure 11 but showing the position of the secondary pinch dies upon completion of the head-forming operation.

20 Figure 13 is a view similar to Figure 8, illustrating a modified mounting for the secondary pinch dies.

Figure 14 is a section on line XIV—XIV of Figure 13.

25 Figure 15 is an end view of Figure 14, with parts broken away in the interest of clarity of illustration.

Figure 16 is an enlarged detail view showing 30 a nail with a duplex head formed by our improved machine.

General.

The machine of the present invention, as hereinafter more fully described in detail, includes 35 means for straightening wire- or rod-like nail stock and advancing it to a head-forming station in predetermined increments. At the head-forming station, primary and secondary pinch dies grip the leading end of the stock while a heading hammer comes in play to form a duplex head, such as shown in Figure 16, at a single blow. Such single-blow head formation is broadly old, and the means for accomplishing this result is therefore not broadly claimed herein. 40 However, in prior art mechanisms excessive wear of parts takes place and the pinch dies and feeding mechanisms heretofore generally used were frequently rendered defective or inoperative due to the continual pounding of the hammer and the inadequate supporting and guiding means for the head-forming dies, and because of the lost motion in the feeding instrumentalities. The 45 present invention provides detailed features of design, structure, and arrangement which pro-

long the useful life of the head-forming dies and feeding mechanism.

Referring in detail to the embodiment of the invention illustrated, 10 represents the bed of the machine which carries suitable bearings 12 supporting a main drive shaft 14 carrying a flywheel 16 and pulley 18 driven from a suitable source of power. The drive shaft has integrally formed therewith crank arms 20 connected by crank pin 22 which operates a connecting rod 24 which is connected by wrist pin 26 secured to a crosshead 28 sliding in suitable guides 30. The crosshead carries a hammer 32 which upon each forward stroke of the crosshead 28, in cooperation with the primary and secondary pinch dies hereinafter referred to, forms duplex head portions h^1 and h^2 on the nail, as shown in Figure 16.

Duplex head forming

A particular feature of the present invention relates to the detailed construction and arrangement of the pinch dies for gripping and forming the duplex head upon the striking of the hammer blow. An upright portion 34 of the bed 10 is formed with an undercut groove 36 to receive the dovetailed portion 38 of a die block 40 which constitutes a removable unit supporting the primary and secondary head-forming dies. The die block has a rearward extension 42 formed thereon, which is threaded to receive an adjusting screw 44 adapted to be manipulated so as to locate the die block and dies carried therein with great precision, the adjusting screw being locked by a jam nut 46.

The die block is apertured at 48 to receive a hardened steel bushing 50 having a tapered passageway 52 extending therethrough, and adapted to accurately guide the advancing length of nail stock S which is fed therethrough in separate increments by the feed carriage and related mechanism to be later described.

An undercut guide shoulder 54 is machined in the die block to provide a slidable guide for the lower surfaces of the primary pinch dies 56 and 58. The upper edges of these pinch dies are inclined to match the inclination of the lower edge 60 of a pair of guide gibs 62 seated against the upper shoulder 64 machined in the die block. The primary pinch die 58 can be moved lengthwise relatively to the guide gib 62 by manipulation of an adjusting screw 66 threaded into a tapped aperture in the die block, the screw 66 being provided with a jam nut 68 for locking it in adjusted position. A gib locking screw 70 passes through a tapped aperture in the die block, bears against the upper edge of the gib 62, and is provided with a lock nut 72. By these means the primary pinch die 58 can be accurately adjusted so that the stock-engaging notch 74 formed in the end thereof is accurately positioned in proper alignment with the guiding aperture 52 formed in the guide bushing 50.

The primary pinch die 56 is slidable along the undercut guide shoulder 54 formed in the die block. This movable pinch die 56 is pushed toward the nail stock by a push rod 76, one end of which engages a notch 78 formed in the die and the other end of which engages an adjusting screw 80 carried by a bell crank 82 pivoted at 84, this bell crank having an arm 86 adapted to be rocked in one direction by a rod 88 the lower end of which engages a socket 93 formed in the upper face of an arm 92 of a lever 94 pivoted at 96. The bell crank is moved in a direction to retract the pinch die holder 56 by means of a rod-like link

95 whose upper end engages an opening 97 formed in the arm 86 of the bell crank and whose lower end passes freely through a lug 90 formed on the arm 92 and has secured thereto a spring 99 bearing on a nut 101 threaded on the lower extremity of the rod-like link 95. The lever 94 carries a follower 98 which coacts with a cam 100 secured to a shaft 102 carrying a gear 104 which meshes with gear 106 secured to the outer end of the main drive shaft 14. The cam 100 and lever 94 thus serve to force the primary pinch die 56 into gripping engagement with the nail stock. For retracting or releasing the grip of the primary pinch die 56, there is a rod 81 with an angular extremity 83 engaging an aperture formed in the pinch die. The opposite end of this rod 81 passes through an opening 87 formed on an extension 89 of the bell crank 82, and an adjustable nut 91 screwed to the extremity of the rod provides means for adjusting the relative position of the movable primary pinch die 56 with relation to its operating bell crank 82.

Slidably mounted in the die block 40 in face-to-face contact with the primary pinch dies 56 and 58 is a pair of coacting secondary holders 108 and 110. These die holders are notched at their outer ends for engagement with push rods 112 and 114 which coact with threaded bolts 116 and 118 formed respectively in levers 120 and 122 pivoted on fixed trunnion studs 124 and 126. The levers 120 and 122 are provided at their ends with rollers 128 and 130 actuated by respective cams 132 and 134 secured to the intermediate shaft 102. A spring 136 is connected at one end to the holder 108 and at its opposite end to the lever 120. A similar spring 138 is connected at one end to the secondary pinch die holder 110 and at its opposite end to the lever 122. With the parts thus arranged, it is apparent that the secondary pinch dies 108 and 110 can be moved into and out of gripping engagement with the nail stock.

For guiding the secondary pinch die holders 108 and 110 we provide pairs of gibs 140 and 142 which are secured by bolts 144 and 146 whose heads are accommodated in counterbores formed in the die block 40, the shank of bolt 144 passing freely through both the gib 62 and the die block, and the shank of bolt 146 passing freely through the die block below the die 58, as shown in Figure 6. The upper and lower edges of the secondary die holders 108 and 110 are tapered, and the inner faces of the gibs 140 and 142 are machined to a corresponding taper. Thus said gibs jointly define an undercut guide groove for the secondary pinch die holders. The fastening bolts 144 and 146 for the gibs 140 and 142 have sufficient clearance in the die block 40 and in the gib 62 to permit of movement relative thereto. This makes it possible to adjust the gibs 140 and 142 toward or from the holders 108 and 110, so as to initially accurately position the parts and also to compensate for wear. Such in-and-out adjustment of the gibs 140 and 142 is effected by manipulation of adjusting screws 148 and 150 which are provided with lock nuts 152 and 154.

The holders 108 and 110 at their inner extremities are formed with guide recesses 156 and 158, to accommodate the secondary pinch dies 160 and 162. Figures 7, 8, and 9 show the preferred construction for mounting the secondary pinch dies in their respective holders, with freedom for movement relative thereto in a direction axial of the nail stock to be acted upon.

Since both pinch dies and the guiding means

therefor are of identical construction, a description of one will suffice for both.

Each recess 156 and 158 is formed with opposite grooves 164, for coaction with guide pins 166 seated in notches 168 formed in opposite faces of the secondary pinch dies. As thus arranged, it is apparent that the secondary pinch dies can partake of a sliding movement within the guide recesses 156 and 158. Coacting with each secondary pinch die is a finger 170 pivoted on a pin 172 mounted in the respective pinch die holder. This finger has a depending arm 174 engaged by one end 176 of a tension spring 178 whose opposite end is secured to suitable anchorage pin 180 carried by the respective pinch die holder. Thus the springs 178, acting through the fingers, tend to press the secondary pinch dies 160 and 162 outwardly from the primary pinch dies 56 and 58 to the position shown in Figure 10.

In the formation of the duplex nail head, the nail stock is gripped at a point spaced a considerable distance from the last cut end thereof. Thus the primary pinch dies firmly grip the nail stock and hold it positively against movement in an axial direction. This condition is illustrated in Figure 10, just prior to the time the secondary pinch dies come into play. As the heading hammer 32 advances toward the nail stock, its forward extremity strikes the cut end *e* of the nail stock. Thereupon the secondary pinch die holders 108 and 110 are moved from the position of Figure 10 to approximately the position of Figure 11, thus causing the secondary pinch dies 160 and 162 to grip the nail stock adjacent the outer end thereof. As the hammer head 32 continues to move toward the nail stock it simultaneously upsets head *h*¹ by reason of the fact that the anvil portions 160^a and 162^a exert an upsetting pressure against the laterally extended body portion of the nail stock. It will be understood that while this action is taking place, the secondary pinch dies 160 and 162 slide relative to the holders 108 and 110, and during this sliding movement they are guided by the pins 166 sliding in the grooves 164. The outer faces of the secondary pinch dies 160 and 162 are formed with recesses 160^r and 162^r, which serve to confine the plastic flow of the outer end of the nail stock so that the combined action of the heading hammer 32 and the recessed secondary pinch dies is to shape the outermost head *h*² on the nail to a predetermined desired contour such as illustrated. As this action takes place, the secondary pinch dies are moved approximately from the position of Figure 11 to the limit of their head-forming movement illustrated in Figure 12, under force of the impact of the heading hammer 32. The heading stroke of the hammer rocks the fingers 170 in a direction to put the springs 178 under tension. Thus upon retraction of the hammer 32 the springs 178 will return the secondary pinch dies to the outer position such as illustrated in Figure 10, it being understood that as the hammer is retracted the secondary pinch die holders move outwardly away from the nail stock to the position shown in Figure 10.

Immediately after the completion of the heading operation and retraction of the primary and secondary pinch dies, the nail stock is advanced axially for a distance equal to the desired length of nail by a feeding mechanism to be later described. Thereupon cutters 182 and 184 (see Figure 3) carried by arms 186 and 188 pivoted at 190 and 192, come into play to sever the nail stock and form the point *p*, as indicated in Figure 16.

Cutting movement is imparted to the cutters 182 and 184 through push bolts 194 and 196 threaded in the free extremity of levers 198 and 200 pivoted at 202 and 204, these levers carrying cam followers 206 and 208 coacting with cams 210 and 212 secured to and moving with the aforementioned crosshead 28. The cutters 182 and 184 are retracted by means of links 214 and 216 connected by universal joints 218 and 220 with said arms 186 and 188, these links having a ball-and-socket connection indicated at 222 and 224, with lugs 226 and 228 on the levers 198 and 200. With the cutter parts constructed and arranged as described, it is apparent that as the connecting rod 24 retracts the crosshead and heading hammer, the cams 210 and 212 will rock the cutter ends of the levers 198 and 200 inwardly, thus shearing and pointing the end of the nail stock. At a succeeding part of the cycle, the cutters 182 and 184 will be retracted, suitable leaf-springs 230 and 232 being provided which are effective to rock the levers 198 and 200 in a direction opposite to that in which they are rocked by cams 210 and 212.

Stock feed

The nail stock *S*, such as rod or wire, is fed in predetermined increments through a series of conventional straightening rollers 234 carried by a sub-frame 236 secured by bolts 238 to the rear of the machine bed proper. This sub-frame 236 is formed with beveled guide tracks 240 which coact with guide portions 242 of a feed carriage indicated generally at 244. This feed carriage has members 246 secured thereto by bolts 248, which members carry rollers 250 journaled on pins 252 secured in yoke portions of said members 246, as shown. The rollers 250 coact with feed cams 254 secured to a shaft 256 journaled in bearings formed in the extremities of bracket 258 bolted at 260 to the rear of the nail machine bed 10. The carriage 244 has mounted thereon a wire gripping tool 262 of conventional form mounted in a suitable holder 264 and adapted to move the wire nail stock longitudinally whenever a forward stroke is imparted to the feed carriage. Feeding movement is imparted to the shaft 256 through a gear 266 secured thereto which meshes with a gear sector 268 keyed to a rock shaft 270. Adjustably secured to the sector 268 is a connection plate 272 having an arcuate tongue 274 fitted in a similarly shaped groove 276 formed in the sector. The connection plate 272 is provided with a pair of elongated slots 278 through which freely pass bolts 280 adapted to adjustably secure the connection plate to the sector in a desired position. The connection plate carries a stud 282 which passes through the end of a link 284 the opposite end of which is connected to a crank pin 286 having a head 288 adjustable in a T-slot 290 formed in the crank disc 292 carried by the aforesaid intermediate shaft 102. As thus arranged it is apparent that by varying the position of the crank pin 286 within the T-slot 290, the desired length of stroke can be imparted to the feed carriage to suit the particular length of nail to be made. In the layout of the machine illustrated, the stroke of the crank pin 286 is sufficient to rock the shaft 270 to an angle of approximately 60°. The pitch radius of the sector 268 is approximately three times the pitch radius of the gear 266. Therefore the stroke in one direction of the crank pin 286 will turn the cam shaft 256 through approximately a half revolution in one direction, and upon the back-stroke

of the crank pin 286 the cam shaft will be retracted for a half revolution. The designed contour of the cams 254 is such that a feeding movement is imparted to the stock by the active parts of the cams between the radial lines o—a and o—b in Figure 2^a for approximately 100° rotary movement of shaft 256. This permits the heading operation to take place when the crank pin 286 is in one dead center position and the cutting operation to take place when the crank pin is in the opposite dead center position (hammer retracted).

The feed table actuating mechanism as described produces essentially a positive delayed action feed because the cam rollers 250 are at all times in firm contact with the cams 254. Thus the length of wire stock fed to the dies is always of a constant length and can be held to unusual close tolerances, thereby producing nails of exactly uniform predetermined lengths. Since the feeding movement of each cam 254 requires only 100°, as indicated by the angle a—o—b in Figure 2^a, of the total 180° movement imparted to the shaft 256 it is apparent that a sufficient concentric dwell portion, for example, 80°, as indicated by the angle a—o—c in Figure 2^a, can be provided on the cam to permit the operation of the primary and secondary dies at the proper time intervals, and because of the adjustable connection between the sector 268 on the connection plate 272, the starting time of the feed stroke can be closely controlled by adjusting the plate 272 relative to the sector 268 and locking the parts by manipulation of the bolts 280. The feed table is retracted by a spring (not shown) acting in a direction opposite to that of the cams 254.

Figures 13, 14, and 15 illustrate a slight modification of the means for mounting the secondary pinch dies. In these figures the secondary pinch die is of dovetail form in plan so as to ride in the undercut recess 294 formed in the outer end of the holder, and a lip 296 is provided to limit the movement imparted to the pinch die by the spring-actuated finger 170. Suitable openings 298 will be formed in the lips 296 to permit the escape of chips or foreign matter.

From the drawings and the foregoing detailed disclosure, it is manifest that the improved machine will make a double-headed nail with a single blow, upon each revolution of the power-driven drive shaft 14.

While we have described quite specifically the design and construction of machine which an actual reduction to practice has shown to be highly practical, it is not to be construed that we are limited thereto, since various modifications and substitutions of equivalents may be made by those skilled in the art without departure from the invention as defined in the appended claims.

We claim:

1. A nail machine comprising a feed carriage carrying a nail stock gripper, a guide for said carriage, means positively advancing said carriage in stock feeding direction for a predetermined time interval and holding said carriage and stock stationary for a predetermined time interval, means for retracting said carriage to starting position, coacting head-forming pinch dies for upsetting a duplex head on the nail stock during the interval it was held stationary, and cutting means for severing the headed nail from the stock advanced by said carriage.

2. A nail machine comprising a feed carriage

carrying a nail stock gripper, a guide for said carriage, means positively advancing said carriage in stock feeding direction for a predetermined time interval and holding said carriage and stock stationary for a predetermined time interval, means for retracting said carriage to starting position, head-forming means for upsetting a duplex head on the nail stock during the interval it was held stationary, cutting means for severing the headed nail from the stock, said head-forming means including coacting primary pinch dies for gripping said nail stock at a distance from the severed end thereof, holders carrying secondary pinch dies for gripping the stock adjacent the severed end thereof, means for supporting the secondary pinch dies with freedom for limited movement relative to said holders in a direction axially of said stock, a hammer effective to strike the severed end of said stock and impart movement to said secondary pinch dies axially of said stock whereby at a single blow of said hammer one nail head is upset between said primary and secondary pinch dies and another nail head is upset between said hammer and said secondary pinch dies, means retracting said holders, and means for retracting said secondary pinch dies axially of the stock after said nail heads have been upset.

3. A nail machine comprising means for advancing wire nail stock axially in predetermined increments, stock-severing means, duplex heading mechanism including primary pinch dies, means effective to cause the latter to grip the nail stock at a distance from the end thereof, holders movable transversely of the nail stock, secondary pinch dies slidable in said holders axially of said nail stock, means limiting the extent of slidable movement of said secondary dies in said holders, and a hammer effective to upset two heads on said nail stock by coaction with said primary and secondary pinch dies.

4. A nail machine comprising means for advancing wire nail stock axially in predetermined increments, stock-severing means, duplex heading mechanism including primary pinch dies, means effective to cause the latter to grip the nail stock at a distance from the end thereof, holders movable transversely of the nail stock, secondary pinch dies slidable in said holders axially of said nail stock, means limiting the extent of slidable movement of said secondary dies in said holders, a hammer effective to upset two heads on said nail stock by coaction with said primary and secondary pinch dies by causing said secondary dies to slide in said holders toward said primary dies, means for retracting said holders, and means for shifting said secondary pinch dies relatively to said holders to starting positions controlled by said limiting means.

5. A nail machine of the character described, comprising a die block, respective fixed and movable primary pinch dies mounted therein, secondary pinch die-holders having recessed portions, said holders being slidably supported in the die block adjacent said primary pinch dies, secondary pinch dies, and means for slidably guiding the latter in the recessed portions of the holder and limiting the slidable movement thereof.

6. A nail machine of the character described, comprising a die block, respective fixed and movable primary pinch dies mounted therein, secondary pinch die-holders having recessed portions, said holders being slidably supported in

the die block adjacent said primary pinch dies, secondary pinch dies, means for slidably guiding the latter in the recessed portions of the holder and limiting the slidable movement thereof, and spring actuated means for shifting said secondary dies to predetermined starting positions in the recessed portions of said holders.

7. A nail machine of the character described, comprising a die block, respective fixed and movable primary pinch dies mounted therein, secondary pinch die-holders having recessed portions, said holders being slidably supported in the die block adjacent said primary pinch dies, secondary pinch dies, means for slidably guiding the latter in said recessed portions of the holders and limiting the slidable movement thereof, and spring-actuated pivotally mounted fingers for shifting said secondary dies to predetermined starting positions in the recessed portions of said holders.

8. A nail machine of the character described, comprising a die block, respective fixed and movable primary pinch dies mounted therein, secondary pinch die holders having recessed portions, said holders being slidably supported in the die block adjacent said primary pinch dies, secondary pinch dies movable in said recessed portions, said secondary dies having notches formed in edge portions thereof, said holders

having grooves facing said notches, and guide pins seated in said notches and adapted to slide along said grooves to guide said secondary dies and limit the extent of travel thereof within the recessed portions of the holders.

9. The combination with a nail machine having coacting pinch dies, a cutter and a reciprocating hammer effective to form a duplex head on nail stock fed thereto, of a delayed action stock feeding means comprising a power-driven member whose movements are synchronized with those of said hammer, a drive plate pivotally connected to said member, a sector adjustably secured to said drive plate and arranged to be oscillated through a predetermined angle by said member, a shaft carrying a gear actuated by said sector, a cam on said shaft, and a nail stock feed carriage actuated by said cam and carrying a nail stock gripper, said cam having an active feed portion effective to advance nail stock to position to be gripped by the aforesaid pinch dies and a passive dwell portion to provide a delay interval of sufficient duration to allow for the actuation of the aforesaid cutter, pinch dies and hammer while said power-driven member is in motion.
